CLARE H. DRAPER, OF HOPEDALE, MASSACHUSETTS, ASSIGNOR TO DRAPER COMPANY, OF HOPEDALE, MASSACHUSETTS, A CORPORATION OF MAINE.

FILLING-REPLENISHING LOOM.

No. 853,199.

Specification of Letters Patent.

Patented May 7, 1907.

Application filed May 19, 1906. Serial No. 317,662.

To all whom it may concern:

Be it known that I, CLARE H. DRAPER, a citizen of the United States, and a resident of Hopedale, county of Worcester, State of Massachusetts, have invented an Improvement in Filling-Replenishing Looms, of which the following description, in connection with the accompanying drawings, is a specification like letters on the drawings representing like parts.

Many looms equipped with automatic mechanism to replenish the running filling are now provided with double detectors, that is, with two instrumentalities to detect filling absence on alternate picks, so that the detecting action takes place on each pick. A loom of this character forms the subject-matter of United States Patent No. 727,014 granted May 5, 1903 to A. E. Stafford, the operation of the filling-replenishing mechanism being effected upon detection of filling absence by either or both of the detecting devices. In a later patent, No. 789,291 granted May 9, 1905 to Northrop, a loom of the double detector, automatic filling-replenishing type is also shown, embodying certain novel features of construction and arrangement, and also providing for the simplification of parts and reduction in cost of manufacture and assembling. Both of these patents show the filling-replenishing mechanism directly controlled by one of the detecting devices, and indirectly controlled by the other detecting device.

My present invention relates to the same general type of double detector loom provided with mechanism to replenish automatically the running filling, and it has for its object the production of means to obviate or overcome certain faulty or improper operations which in practice occur at times in loom of the type specified.

Upon careful consideration of the operation of a double detector loom it will be clear that, theoretically, so long as the running filling is intact and properly laid each detector should detect presence of filling on its own detecting pick, and if on one pick one detector detects filling absence the other detector should detect such filling absence on the next pick. That is, for the proper action of the detecting instrumentalities, there must always be indication of the presence of filling by the two detectors in succession when the

filling is present, or the two detectors must 55 successively indicate filling absence after failure of the filling has been detected by either detector. If, then, one detector indicates presence of filling and on the next pick the other detector fails to indicate such 60 presence of filling, the latter being present as a matter of fact, there is an abnormal or improper action of the detectors. So, too, upon failure of filling, if one detector detects and indicates filling absence, and on 65 the next pick the other detector fails to detect such filling absence, the detector action is abnormal.

As a matter of fact there are four conditions of abnormal or improper detector action in a double detector loom:

A. The left-hand detector detects filling absence, while on the next pick the right-hand detector fails to detect such absence of filling.

B. The right-hand detector detects filling absence, while on the next pick the left-hand detector fails to detect filling absence.

C. The right-hand detector indicates filling absence, though there is filling present, while 80 on the following pick the left-hand detector detects presence of filling. Such action of the first-named detector may be due to slack or kinky filling, or the detector may catch and fail to act properly.

D. The left-hand detector indicates filling absence when the filling is present, while on the next pick the right-hand detector gives the proper indication, such action resulting from the causes mentioned in case C.

I have herein so constructed and arranged the mechanism that upon the occurrence of any of the abnormal detector actions hereinabove referred to the loom will be stopped automatically.

Improper or abnormal action of the detectors or forks of a double detector loom may result in (a) thin places in the cloth, caused by (1) the fork-tines striking the grid or grate, (2) lint in the grid, (3) trailing thread 100 or filling-end from the cloth, (4) trailing thread from the shuttle, (5) reel or shuttle mis-threads; (b) thick places in the cloth, caused by co-operation of the right-hand fork and its actuator or weft-hammer, through 105 failure of the filling to tilt the fork; (c) unnecessary filling transfers or changes caused by the co-operation of the left-hand fork with

its actuator, through failure of the filling to tilt the fork, (this also makes a thick place in the cloth). In each of the foregoing cases it will be found that one fork is tilted, and the other fork is not tilted on the next succeeding pick, abnormal action of the forks thus taking place.

Regarding the failure of the fork to tilt when filling is present it may be stated that if the cam which operates the actuator or weft-hammer is set incorrectly the hook will co-operate with the fork-tail before the filling can tilt the fork, so that a filling absence indication is made when actually filling is present. Relative to the formation of thin places in the cloth it will be understood that in looms of the double detector type under discussion take-up is arrested when a fork detects filling absence, and consequently if a fork fails to detect such absence there will be no arrest of take-up and a thin place results. As to the formation of thick places, if a filling absence indication is made by a fork when filling is present the take-up is arrested, and the thick place results.

In my present invention I have provided means whereby the loom will be stopped automatically whenever the action or operation of the detectors is abnormal, as will be fully described hereinafter in the subjoined specification, and the various novel features of my invention will be particularly pointed out in the following claims.

As will appear hereinafter the present construction is such that filling replenishment is controlled by only one of the detectors, thereby differing from the structures in the patents referred to, but arrest of take-up is effected by or through filling absence detection by either detector.

Figure 1 is a top plan view, centrally broken out, of a portion of an automatic filling-replenishing loom embodying my present invention, the filling-detecting devices and parts co-operating therewith or controlled thereby being shown in normal position; Fig. 2 is an enlarged left-hand side elevation of the main filling-detector and adjacent parts in the same relative position shown in Fig. 1, with the knock-off lever for the shipper in section; Fig. 3 is a similar view but showing the position of the parts just after the main detector has indicated filling absence; Fig. 4 is a like view showing the return of the main detector-slide to its rear-most position after having been moved into the outward position shown in Fig. 3, and the loom will be stopped on the next following pick, as will be explained; Fig. 5 is a similar view of the parts shown in Figs. 2, 3 and 4, the main detector having indicated filling absence and then the auxiliary or right-hand detector has indicated such absence, both detectors working properly so that loom stop-

parts as in Fig. 5 preventing actuation of the knock-off lever, as will be described; Fig. 6 is a partial longitudinal sectional view of the mechanism shown in Fig. 2 and in the same relative position, the nearer side of the rear part of the fork-slide being broken out; Fig. 7 is a detail partly in elevation and partly in section, of the parts illustrated in Fig. 5, and showing the manner of resetting the same automatically from the position shown in Fig. 5 to that shown in Figs. 2 or 6. In the position shown in Fig. 7 both detectors have detected filling absence, (which is a proper detector action) and consequently the parts are to be reset without stopping the loom; Fig. 8 is a side elevation of one member of the two part main slide; Fig. 9 is a top plan view thereof; Fig. 10 is a like view of the second member of the main slide; Fig. 11 is a side elevation of such second member; Fig. 12 is a top plan view of the controller for the shipper-releasing latch.

As has been hereinbefore stated the loom in which my present invention is embodied is provided with two filling-detecting devices or instrumentalities, so that when properly operating each pick is a detecting pick, and I have herein shown means adapted to arrest the operation of a take-up instrumentality upon filling absence detection by either detecting device, the latter being shown of the well known tilting fork type.

So far as concerns the right-hand or auxiliary detecting device it may be of usual construction, and as shown in Fig. 1 comprises a tilting detector or fork g and its slide g^x longitudinally movable in the fixed guide g^z , the fork-tail g^{20} being adapted to co-operate with the hook w^x of an actuator or weft-hammer W^x upon failure of the fork to be tilted on the detecting pick of such fork. Upon co-operation of the fork and weft-hammer the slide g^x is moved outward against the action of its returning spring s^x , and the arm d^x is swung outward to turn the rock-shaft d' (on which said arm is fast) in the direction of arrow 250, Fig. 2, arresting take-up. This is effected through arm d^z , fast on the rock-shaft and having a lateral lug d^y , Fig. 2, to engage the take-up pawl carrier a' , and thereby disengage the pawl from the usual ratchet, substantially as provided for in the Patent No. 789,291 before referred to, but as the weft-hammer W^x is forward the lateral lug d^y thereon prevents the shuttle-feeler y^x from moving back, and a change of filling is prevented, as in United States Patent No. 805,497 granted November 28, 1905 to Stafford.

Referring to Fig. 1 the lay A^3 provided with shuttle-boxes B , B^x , the automatically self-threading shuttle S^x , the filling-replenishing mechanism, including the transfeerer F' and the filling-feeder F (partly shown at the right hand side of the loom) and the con-

trolling rock-shaft d' , which governs the operation of the replenishing mechanism; the shipper S , its notched holding plate N and the releasing device for the shipper, shown as a knock-off lever N^x fulcrumed at n^x , may be and are all of usual construction in the "Northrop" type of loom such as shown in United States Patent No. 529,940, dated November 27, 1894, and operate in a manner familiar to those skilled in the art. As will be manifest the detecting devices are located at opposite sides of the cloth, the auxiliary detector or fork g at the replenishing side of the loom and the main detector f at the shipper side, such detector being shown as a tilting fork of familiar construction. The main fork-slide, and adjacent parts, are of novel construction in my present invention and will be described in sufficient detail to clearly explain the operation of the apparatus. The main fork-slide comprises two members, one of which is movable with and also relatively to the other, the fork sustaining member being clearly shown in Figs. 8 and 9 as an elongated flat plate 1 provided at its rear end with upright parallel and laterally-separated cheeks 2 between which the fork is fulcrumed, the rear end of the plate being open at 3 for the weft-hammer or actuator W , provided with a hook w , Figs. 1, 2, 6 and 7. The hook is slidably supported on a cross-bar 4 between the cheeks 2 and co-operates with the main fork-tail f^x when the main fork is not tilted on its detecting pick, so that the forward stroke of the weft-hammer W will move outward the fork-supporting member 1 of the slide. Said member has a transverse shoulder 5 on its under side, and a forward extension 6 to bear against the retracting spring s , the shoulder 5 engaging the front end of the fixed stand or guide 7 and limiting return movement of the slide-member 1, Figs. 6 and 7.

The side walls of the guide 7 are in practice provided with internal, longitudinal grooves to receive elongated ribs 8 on the cheeks 2, clearly shown in Figs. 8 and 9, which prevent any lifting of the slide member and guide it in its longitudinal movement, while supporting its rear end, for the bottom 9 of the guide extends for only a part of the full length of the latter, Figs. 6 and 7, and it is provided with an upturned abutment 10 which passes freely through the slot-like extension 3 x of the opening 3. The other or front member of the main slide is shown separately in Figs. 10 and 11 and is made as a casting having parallel upright sides 11, connected at the bottom and deeply notched at their front ends at 12, and upturned at their rear ends at 13 and connected by a cross-bar 14, the sides being reduced in thickness at 15, Fig. 10 and having on their inner faces opposite lugs 16 for a purpose to be described. Longitudinal, ex-

ternal ribs 17 on the thinner portions 15 of the sides are provided to freely enter and slide in corresponding grooves in the stand or guide 7, in practice the front member of the slide rests upon the plate-like member 1, as shown best in Figs. 6 and 7. The front ends of the cheeks 2 form upright shoulders or abutments 2 x which engage the rear end of the other member of the slide when said two members are in normal relative position, as in Fig. 1.

Between the sides 11 I have fulcrumed at 18 a resetting device, shown as a knuckle-shaped block 19, 20, the part 20 being adapted to at times rise above the tops of the sides 11 for a purpose to be described, the operative movement of such device being limited by the beveled end 21 of the base portion 19 thereof coming into engagement with the part of the casting connecting the sides 11. The use and operation of such resetting device will be described hereinafter. An arm d fast on the rock-shaft d' is upturned and provided at its upper end with a lateral bend d^x which enters the deep notch 12, as in Figs. 1 and 2, outward movement of the main slide as a unit turning the rock-shaft d' as usual to effect the operation of the replenishing mechanism.

From the foregoing it will now be clear why the actuation of the replenishing mechanism is only effected by or through detecting action of the main detector, for if the auxiliary fork g detects filling absence its slide moves forward and arrests take-up, while the holding back of the shuttle-feeler y^x prevents replenishment of filling, detecting action of the main fork f , however, acting to arrest take-up and also to cause filling replenishment. When the auxiliary fork detects and causes the rock-shaft d' to turn in the direction of arrow 250, Fig. 2, the arm d will move the front member of the main slide outward, changing its position relative to the other slide member 1 and acting upon the controller for the shipper-releasing latch, to be described, but filling replenishment will not be effected.

The tops of the sides 11 are each provided with a series of notches or depressions 22, 23, 24, the middle notches 23 being much deeper than the innermost and outermost notches, and the notches co-operate with a latch-carrier mounted on the front member of the main slide, the carrier being made as a casting and being movable longitudinally upon and also with said slide member. Said latch-carrier is shown as an elongated body 25 having its front end extended to form a finger-piece 26 beyond, a cross-bar 27 extended laterally from opposite sides of the body and beveled on its under side, at 28, Fig. 6, to form a detent, a latch 29 being pivotally mounted at 30 on one end of said bar. The cross-bar is reduced in thickness to accommodate the

latch and presents a shoulder 31, shown clearly in Figs. 2 to 5, to prevent the latch from dropping down out of position. The latch depends outside one of the sides 11 of the front member of the main slide, as shown, and is arranged to co-operate at times with the adjacent end of the knock-off lever N^x to rock the latter and release the shipper. The inner end of the carrier-body is enlarged laterally at 32, and on its under side is provided with two depending lugs 33, and transverse shoulders 34, 35, the latter being formed on an upturned head or bunter 36, while on the upper side of the enlargement 32 is a transverse stop or safety rib 37, and at the forward end of said enlargement two lateral, oppositely-extended lugs 38 are provided.

When the parts are assembled the enlargement 32 passes beneath the bar 14 and between the rear portions 17 of the sides of the front member of the main slide, the detent 28 co-operating with one or other of the several notches 22, 23, 24, according to the position of the latch-carrier, the notches serving as detent-stops in the operation of the device; the inner or rear end of the carrier being supported on the fixed abutment 10.

Normal position of the carrier is shown in Figs. 1, 2 and 6, and at such time the detent 28 co-operates with the pair of notches 24, while the lugs 33 rest on the inturned projections or lugs 16, the shoulder 35 being behind the abutment 10, the upper end of the bunter or head 36 then being close behind the bar 14, limiting forward movement of the latch-carrier on the front slide member. At the same time the latch 29 is in inoperative position with relation to the knock-off lever. It may be stated at this point that the spring s normally maintains the two members of the main slide pressed together at the shoulders 2 x , the slide as a whole being retracted and in its rearmost, normal position. When the parts are so positioned the main slide will be moved outward as a unit if the tail f^{20} of the main fork f is engaged by the hook w of the weft-hammer W , upon the outward or active stroke of the latter. If, however, the auxiliary slide g^x is moved outward the arm d will be swung and it will slide forward the front member of the main slide, leaving the rear and larger member 1 quiescent. Now let it be supposed that the main fork is not tilted on its detecting pick, then the main slide is moved outward as a unit, and as it moves the latch-carrier will move with it until the shoulder 35 engages the abutment 10, stopping the carrier while the slide completes its movement, the lugs 33 dropping off and behind the lugs 16. This causes the detent 28 to draw out of the front pair of notches 24 and to drop into the deep notches 23, this condition of affairs being shown in Fig. 3, the end of latch 30 hanging down in front of the

knock-off lever N^x . The weft-hammer W returns and the spring s retracts the main slide, the latch lifting over the lever N^x and dropping behind it in operative position, see Fig. 4, in readiness to actuate the knock-off lever and release the shipper.

It will be seen by reference to Fig. 4 that the shoulder part 32 of the carrier rests on the abutment 10 and the shoulder 34 is behind said abutment and in position to be engaged thereby under certain conditions. Remembering that the weft-hammers W , W^x move oppositely it will be clear that the latter is on its forward or active stroke while the main slide is returning after having been moved outward. It has been supposed that the fork f has not been tilted, and consequently the main slide was moved outward, positioning the parts as in Fig. 3, and first it will be supposed that the auxiliary fork g is not tilted, or in other words, that both forks act successively in the same manner, that being termed by me their normal action. As fork g is not tilted its slide g^x is moved outward as the main slide begins to move back, but the arm d will arrest the retractive movement of the front member of the main slide before the latch 29 can draw over and drop behind the end of lever N^x , and the said front member will be drawn forward, taking the latch-carrier with it until the shoulder 35 catches on abutment 10. The carrier is then held and the detent 28 is caused to pull out of the deep notches 23, draw over the upper edge of the resetting device 19, 20 and drop into the shallow notches 22, as shown in Fig. 5, and by inspection of that figure it will be seen that the latch 29 is now held above and out of range of the knock-off lever. The outward movement of the main slide as a unit turned the rock-shaft d' to cause filling replenishment when the shuttle reached the replenishing side of the loom, and that having been effected loom stoppage is not desired, under proper conditions. Consequently, the parts having been placed in the position shown in Fig. 5, the return of both members of the main slide to normal position does not alter the relative position of the latch-carrier until the weft-hammer W again moves forward, the new filling having tilted fork f . As the weft-hammer moves forward it will strike the bunter 36, see Fig. 7, and push forward the latch-controller, the detent 28 acting upon the upper end of the resetting device and swinging it forward on its pivot 18. This movement of the resetting device lifts the latch-carrier to carry the latch above and entirely clear of the knock-off lever, and the lugs 33 ride up onto the co-operating lugs 16, the movement of the latch-carrier carrying the detent forward free of the resetting device and causing the detent to drop into the notches 24, while the resetting device drops back by gravity into normal position.

The parts are thus restored and no stoppage of the loom has been effected.

If the right hand fork first detects filling absence, followed by like action of the left-hand fork, which is normal fork action, loom stoppage will not be effected, for outward movement of slide *g* acts through the rock-shaft *d'* and arm *d* to pull outward the front member of the main slide, and the first 10 change in the relative position of the latch-carrier is effected, the latch 29 then depending in front of the lever *N^X*. Now the slide *g* begins to go back, on the next pick, but the left-hand fork *f* detects filling absence and 15 its tail is caught by hook *w*, moving the main slide member 1 forward, and its shoulders 2 engage the front member before the latter has moved back far enough to cause the latch to drop behind the knock-off lever *N^X*, 20 and both members of the main slide then complete outward movement together, to the position shown in Fig. 3, and filling replenishment is provided for by or through the main detector action. On the return of 25 the main slide to the position shown in Fig. 4 the latch is in its operative position, but the presence of the new filling is detected, the forks are tilted, and the weft-hammer *W* acts as before described against the bunter 36, to effect resetting of the controller. 30 When the first change in the relative position of the latch-carrier and the main slide occurs the safety rib or stop 37 is brought against the bar 14, and acts to prevent too 35 much of a movement of the carrier, its position relative to the bar 14 being shown in Figs. 3 and 4, and on the change of the detent to the innermost notches 22 the lateral extensions 38 co-operate, for the same purpose, with the upturned portions 13 of the front member of the slide.

The operation of the mechanism has been explained when both detectors or forks act successively to indicate filling absence, stoppage of the loom being avoided, and now the operation of the mechanism upon abnormal detector action will be explained. In the preceding reference to case (a), the formation of thin places, in the four causes mentioned, the left-hand fork is tilted and the right-hand fork is not tilted, and vice versa. In the fifth cause, viz.—a real mis-thread, that is, a failure of the new filling thread to enter the shuttle-eye, when the freshly replenished shuttle is picked to the shipper side of the loom the filling is present and tilts the left-hand fork *f*, although the thread does not enter the shuttle-eye. On the next pick, to the replenishing side, the filling is broken, but the right-hand fork *g* will be tilted by the filling-end extending from the cloth to the hopper, shown at *t*, Fig. 1, and it may be that this filling-end will remain in position and tilt the fork *g* for a number of 60 picks, owing to what may be a tardy action

of the thread cutter *t^X* on the temple *T*, Fig. 1. Going back to the first pick in which the filling-end *t* tilted fork *g*, on the following pick to the left fork *f* will not be tilted, and the abnormal fork action occurs, one fork indicating filling presence and the other fork detecting its absence on the succeeding pick, instead of a filling absence indication by both picks. When the fork *f* thus detects filling absence a replenishment of filling will be effected, but on this pick to the right, (the third pick of the sequence) the fork *g* will be tilted by the filling end. On the return, or fourth pick, to the left, fork *f* is again tilted, but the loom will be stopped by 70 engagement of the weft-hammer *W* with the bunter 36 of the latch-carrier, as will now be made clear. First, however, it will be stated that the temple thread-cutter is very often, though not properly, set so as to cut the new filling-end after the first two or three picks after transfer, the setting of the temple determining the time of action of the thread-cutter, for the further forward toward the front of the loom the temple is set the later 75 80 85 90 95 will the temple thread-cutter act, and vice versa.

Returning to the mechanism, supposing a real mis-thread has occurred after a transfer of filling, and the thread has broken on the pick to the right, but fork *g* has been tilted by the filling-end *t*, while on the next pick fork *f* detects filling absence, and consequently the main slide is moved outward as a unit, and the parts are positioned as in Fig. 3, filling replenishment being called for. On the next pick to the right, the filling-end *t* again tilts fork *g*, so that its slide remains quiescent, and fresh filling is inserted in the shuttle, which is now picked to the left, and as there is then filling present the fork *f* will be tilted, but on the return of the main slide the parts are positioned as in Fig. 4. Fork *f* being tilted the weft-hammer *W* moves forward and strikes the bunter 36, pushing forward the latch 29 against the adjacent end of the knock-off lever *N^X* and rocking said lever to release the shipper *S* and thereby stop the loom. This gives the weaver notice that there is some fault to be corrected, and prevents the formation of a thin place, for it will be obvious that if the right-hand fork is tilted (by the filling-end, or by any thing else, as for instance, the fork-tines striking the grid,) when the running filling is absent, take-up will not be arrested on that pick and if the loom is not promptly stopped a thin place will be formed. I have thus provided means to indicate non-detecting action of the detector when filling is absent. Should either grid become choked with lint, so that its fork will be tilted by the lint, even when filling is absent, the loom will be stopped. If a broken thread trails from the shuttle it will cause an abnormal action of the detectors 100 105 110 115 120 125 130

and loom stoppage will follow. When the thread breaks and trails the trailing end is often long enough to tilt the main fork *f*, but on the opposite pick, the eye of the shuttle being at the right-hand end of the shuttle the trailing end will not be long enough to tilt the auxiliary fork *g*; thereby preventing the abnormal fork action. As fork *g* detects filling absence its slide, moving outward, will cause the front member of the main slide to move outward and the latch-carrier will have its first relative movement, but on the next pick to the left the trailing end will tilt fork *f*. Now, as there is nothing to move outward the other member 1 of the main slide the front member thereof will have returned to the position shown in Fig. 4, with the latch 29 ready to operate, and as weft-hammer *W* comes forward it strikes the bunter 36, moving the latch-carrier forward and operating the knock-off lever *N*^x to stop the loom.

The operation of the apparatus when any one of the five causes for making a thin place under case (a) occurs has now been explained, and it will be manifest that if the fork *f* is tilted and fork *g* fails to be tilted, when filling is absent, the mechanism will operate to effect loom stoppage. When either fork-slide is moved forward by co-operation between the tail of its fork and the weft-hammer hook the latch-carrier will be given its first relative movement, dropping the detent 28 into the deep notches 23. If, then, the other fork-slide is moved outward the latch-carrier will be given its second relative movement and the detent will be carried into the notches 22, from which position the latch-carrier will be carried forward, by the action of the resetting device and the weft-hammer *W*, into its normal position, both fork slides returning to their normal positions. This is the operation during normal filling replenishment, as has been previously described.

If the main fork *f* first detects filling absence the parts assume the position shown in Fig. 3, and the rock-shaft *d*' is turned to effect filling replenishment; and if for some reason the auxiliary fork *g* is tilted the relative position of the latch carrier will not be changed. After the fresh supply of filling is inserted in the shuttle the latter is picked to the shipper side, and the new filling tilts fork *f*, so that the weft-hammer *W* comes forward, strikes the bunter 36 (the parts being positioned as in Fig. 4,) and the forward movement of the latch-carrier brings the operationally-positioned latch 29 against the knock-off lever *N*^x and releases the shipper to stop the loom. Similarly, if the fork-slide *g* moves outward first the latch-carrier is moved to bring the detent into the notches 23, the front member of the main slide being moved forward by itself, and if then the fork *f* is tilted the weft-hammer *W* will cause loom stoppage as just described. The position of the

knock-off lever will show the weaver whether stoppage of the loom was or was not due to the detector stop-motion, and when it shows that such stop-motion was the cause of stoppage the weaver has his attention called thereby to an abnormal detector or fork action, preventing the formation of faulty cloth by giving an opportunity for remedying the abnormal action and also for removing the source of such action.

In case (b), relating to the formation of thick places in the cloth, caused by co-operation of the tail of the right-hand fork *g* with the hook *w*^x, notwithstanding the fact that filling is present, it will be manifest that this faulty action is local to the right-hand detecting device, and consequently the left-hand fork is tilted on the next pick, the abnormal fork action thus occurring. When fork *g* failed to tilt the take-up was arrested, and should loom stoppage not be effected a thick place would inevitably be formed in the cloth. The filling absence indication of fork *g* results, however, in outward movement of the front member of the main slide and the first relative change in the latch-carrier, as previously explained, and on the next pick, (the parts then being in the position shown in Fig. 4) the forward stroke of weft-hammer *W* will act through the latch-carrier to actuate the knock-off lever *N*^x and release the shipper, stopping the loom.

In case (c) relating to unnecessary filling replenishments when the filling is intact and present, caused by the main or left-hand fork co-operating with the hook of its weft-hammer, thick places will be formed and the replenishing mechanism is operated when such operation is wholly unnecessary, if provision is not made for loom stoppage. In such case the failure of the fork *f* to tilt when filling is present is due to some local cause such as a kink, or slackness, in the filling, and when the said fork gives a filling absence indication, the filling being present, the main slide is given the unitary outward movement, and the parts are positioned as in Fig. 3, while replenishment is called for. As fork *g* detects presence of filling the slide *g*^x remains quiescent and the main slide moves back as a unit, to the position shown in Fig. 4, with the latch 29 ready to engage lever *N*^x. It is probable, however, that inasmuch as the fork *f* failed to operate properly, *i. e.*, to give the correct indication, on the first pick above referred to, because of some local cause, as before specified, the fork will operate properly on its next detecting pick, a fresh supply of filling having been inserted in the shuttle, and the weft hammer *W* will engage the bunter 36, and through the latch loom stoppage will be effected, affording the weaver an opportunity to correct the fault. The formation of a thin or a thick place in ordinary plain weaving for a single pick is not material,

as such a thick place does not show, and the loom can be let back for such a thin place, but in the better grades of cloth such places are objectionable and expensive, the greater 5 the extent of the thick or thin place the more objectionable and expensive.

By my invention the prompt stoppage of the loom checks the faulty formation practically at its inception, so that instead of the 10 fault continuing it is stopped promptly and can then be readily corrected.

So far as I am aware I am the first to devise means, in a double detector loom, to detect improper or abnormal action of the filling 15 detectors; to stop or cut short the formation of thin places in the cloth, and to detect such formation by or through means independent of the cloth; to prevent the formation of thick places by or through means 20 acting independently of the warp tension; to detect and stop the unnecessary operation of the filling replenishing mechanism when the running filling is intact; and to detect trailing threads from either the shuttle or the 25 cloth, and upon such detection cause loom stoppage. My invention, accordingly, is not restricted to the precise construction and arrangement herein shown and described, as the same may be varied or modified in different 30 particulars by those skilled in the art without departing from the spirit and scope of my invention. I believe that it is also broadly new to provide a bi-part detector slide which may have a unitary movement in 35 either direction, or a differential movement, one part or member of such slide moving relatively to the other member at such time.

Having fully described my invention, what I claim as new and desire to secure by Letters 40 Patent is:

1. In a loom, means to detect filling absence on each pick, and means adapted to cause stoppage of the loom immediately upon detection of filling absence on one pick and 45 failure to detect such filling absence on the next pick.

2. In a loom, two filling detectors, located at opposite sides of the loom and acting on alternate picks, and means adapted to effect stoppage of the loom immediately upon failure of both detectors to act in the same manner on two successive picks, the actual condition of the filling being the same on each pick.

3. In a loom provided with mechanism to automatically replenish filling, means to effect stoppage of the loom upon the operation of said mechanism when the filling is intact.

4. In a loom, means acting independently of the warp tension to effect stoppage of the loom when the formation of a thick place is initiated and the filling is intact.

5. In a loom provided with automatic filling-replenishing mechanism, means, operative independently of the cloth and including 65 a detector to detect the absence of filling, to

effect stoppage of the loom when the formation of a thin place in the cloth is initiated by improper detecting action of the detector, the filling being absent.

6. In a filling-replenishing loom, a detector 70 to detect the absence of filling, and means to effect stoppage of the loom when such detecting action takes place improperly.

7. In a loom, a detector to detect filling absence, and means to indicate improper detecting action of such detector. 75

8. In a loom, a detector adapted to engage and be moved by intact filling when properly laid, and means to indicate failure of such detector movement when the filling is present. 80

9. In a loom, a tilting detector to engage and be tilted by intact filling, and means to indicate failure of the detector to tilt notwithstanding presence of filling. 85

10. In a loom, a detector to detect filling absence, and means to indicate non-detection by such detector when filling is absent.

11. In a loom, filling-replenishing mechanism, two filling detectors, at opposite sides of 90 the loom, means to control the operation of said mechanism by or through one only of the detectors, and means adapted to effect stoppage of the loom immediately upon the occurrence of abnormal operation of the detectors. 95

12. In a loom, in combination, two filling-detectors normally adapted to indicate presence or absence of filling on alternate picks, filling-replenishing mechanism controlled as 100 to its operation by filling absence indication of one of the detectors, a shipper, and means to release the same when either detector fails to indicate filling absence on the pick following such an indication by the other detector. 105

13. In a loom, in combination, two filling-detectors normally adapted to indicate presence or absence of filling on alternate picks, filling-replenishing mechanism controlled as 110 to its operation by filling absence indication of one of the detectors, and means adapted to effect stoppage of the loom automatically when the condition of the filling indicated by one detector is immediately followed by indication of a different condition by the other detector, the condition of the filling being unchanged. 115

14. In a loom, in combination, two filling-detectors each adapted to arrest the operation of a take-up instrumentality upon detection of filling absence, filling-replenishing mechanism controlled as to its operation by one of said detectors, a shipper, a knock-off lever to release it, a latch to actuate the said lever, and means to operate said latch when on successive picks the detectors indicate different conditions of the filling while the filling condition remains unchanged. 125

15. In a loom, in combination, two filling- 130

forks, a slide for each, an actuator for each slide, filling-replenishing mechanism controlled as to its operation by one of the forks, a shipper, and means to release the same by or through the movement of one of said actuators when on successive picks the forks indicate different conditions of the filling while the filling condition remains unchanged.

16. In a filling-replenishing loom, two filling-detecting devices to detect the condition of the filling on each pick, each device including a filling-fork and its slide, and a weft-hammer, a shipper, means to release it, a latch and a latch-carrier, and means to cause direct and immediate co-operation of one of the weft-hammers and the latch-carrier to actuate the latch when detection of filling absence by one fork is immediately followed by tilting of the other fork.

17. In a loom, in combination, two filling-forks, a slide for each, one of said slides having two members capable of unitary and differential movement, filling-replenishing mechanism controlled as to its operation by unitary outward movement of the two-part slide, means to effect differential outward movement of the latter by or through detection of filling absence by the other fork, and means to cause stoppage of the loom when such differential movement of the slide is immediately followed by indication of filling presence by its fork.

18. In a loom, in combination, two filling-forks, a slide for each, one of said slides having two members capable of unitary and differential movement, filling-replenishing mechanism controlled as to its operation by unitary outward movement of the two-part slide, due to detection of filling absence by its fork, means to effect differential outward movement of said slide through detection of filling absence by the other fork, and means to cause stoppage of the loom when unitary outward movement of the slide is followed immediately by indication of filling presence by the other fork.

19. In a loom, in combination, main and auxiliary filling-forks, at opposite sides of the loom, a slide for each, the main slide comprising two members capable of unitary and differential movement, filling-replenishing mechanism controlled by unitary outward movement of the main slide, means to effect differential movement of the main slide members upon filling absence indication by the auxiliary fork, a latch, a latch-carrier on one of the slide members and movable relatively thereto, a shipper, a knock-off lever therefor, and means to move the latch-carrier to operatively position the latch with relation to said lever and move the latter when filling absence indication of one fork is immediately followed by indication of filling presence by the other fork.

20. In a loom, in combination, main and

auxiliary filling-forks, at opposite sides of the loom, a slide for each, the main slide comprising two members capable of unitary and differential movement, filling-replenishing mechanism controlled by unitary outward movement of the main slide, means to effect differential movement of the main slide members upon filling absence indication by the auxiliary fork, a latch, a latch-carrier on one of the slide members and movable relatively thereto, a shipper, a knock-off lever therefor, means to move the latch-carrier to operatively position the latch with relation to the lever when filling absence is indicated by either fork, and means to automatically return said latch-carrier to normal position without acting upon the knock-off lever when filling absence indication by one fork is immediately followed by a like indication by the other fork on the next pick.

21. In a loom, two filling-detectors to detect presence or absence of filling on alternate picks, and means adapted to cause the operation of a loom-stopping instrumentality immediately upon the occurrence of contrary indications of said detectors on successive picks when the filling is present, or after filling absence indication by either detector.

22. In a loom, two filling-detectors to detect presence or absence of filling on alternate picks, and means adapted to cause the operation of a loom-stopping instrumentality immediately upon the occurrence of contrary indications of said detectors on successive picks when the filling is present or after failure thereof.

23. In a loom, two filling-detectors to detect presence or absence of filling on alternate picks, and each adapted to arrest the operation of a take-up instrumentality upon detection thereby of filling absence, filling-replenishing mechanism controlled as to its operation by one of the detectors, a shipper, and means to release it immediately upon the occurrence of contrary indications of said detectors on successive picks when the filling is present or after detection of filling absence by either detector.

24. In a loom, two filling-detectors to detect presence or absence of filling on alternate picks, and means to effect a change in the operation of the loom immediately upon the occurrence of contrary indications of said detectors on successive picks when the filling is present or after filling absence indication by either detector.

In testimony whereof, I have signed my name to this specification, in the presence of two subscribing witnesses.
